HARRY A. FOOTHORAP, OF HARRISBURG, PENNSYLVANIA, ASSIGNOR TO ELLIOTT-FISHER COMPANY, OF HARRISBURG, PENNSYLVANIA, A CORPORATION OF DELAWARE.

PLATEN AND PLATEN EQUIPMENT FOR TYPE-WRITING MACHINES.

1,203,518.

Specification of Letters Patent. Patented Oct. 31, 1916.

Application filed February 6, 1911. Serial No. 606,934.

To all whom it may concern:

Be it known that I, HARRY A. FOOTHORAP, a citizen of the United States of America, residing at Harrisburg, in the county of 5 Dauphin and State of Pennsylvania, have invented certain new and useful Improvements in Platen and Platen Equipment for Type-Writing Machines, of which the following is a specification.

10 This invention relates to what are known as flat platen typewriters, and more particularly to the mounting of the platen and to means whereby a ribbon extended over the platen is automatically fed step by step as 15 the platen is manipulated.

One object of the invention is to provide a simple, inexpensive and efficient mounting whereby the platen is yieldingly sustained in writing position and permitted a downward 20 movement from the writing plane when operated by a treadle.

A further object is to combine with a 25 depressible platen a ribbon having its opposite ends wound upon rolls and line spaced automatically by line spacing mechanism operated by the platen when the latter is depressed to facilitate the adjustment or replacement of work sheets.

Other objects subordinate to those enumerated will hereinafter appear.

In the accompanying drawings—Figure 1 is a bottom plan view of the platen frame and the structure carried thereby including the platen. Fig. 2 is a sectional view of a 35 portion of the structure showing more particularly the line spacing mechanism with the parts in the positions they assume when the platen is in normal or elevated position. Fig. 3 is a similar view with the platen depressed. Fig. 4 is a longitudinal section on the line 4—4 of Fig. 1. Fig. 5 is a transverse section on the line 5—5 of Fig. 4, with the center portion of the structure broken out to facilitate illustration. Fig. 6 40 is a detail sectional view showing more particularly the mounting and relation of one of the platen guide rollers. Fig. 7 is a detail view of one end of one of the spring supporting bars. Fig. 8 is a detail perspective 45 view of the line space lever and pawl, and Fig. 9 is a transverse section showing the manner in which a folded form is made to inclose the ribbon and is retained by the co-

action of the platen with one of the stationary work clamps.

1 indicates a stationary platen frame comprising side bars 2 and 3 and transverse frame bars 4, 5 and 6 having their upper edges located in a lower plane than the upper edges of the side bars 3.

The bar 4 is located at the rear end of the platen frame while the bars 5 and 6 are located adjacent to the front and rear ends of a vertically movable or depressible platen 7 approximately fitted between the side 65 plates 2 and 3 of the frame and yieldingly supported by springs 8 preferably located at or adjacent to the four corners of the platen. The pair of springs 8 at each end of the platen are seated upon spring supporting 70 bars 9 and have their upper ends received within spring cups 10 screwed or otherwise secured to the under side of the platen. Projecting upwardly into the springs from the bars 9 are combined spring-centering and 75 platen-stop pins 11. The pins 11 prevent displacement of the springs from the bars 9 and also serve by engagement with the platen, or a part carried thereby, as for instance screws 12, to limit the downward 80 movement of the platen when the latter is depressed by means to be described.

The screws 12 serve to retain the spring cups 10, but it will also be seen that these screws constitute adjustable platen stops co- 85 acting with the stops 11 to limit the depression of the platen, the extent of such depression being variable, if desired, by the adjustment of the screws 12. The upward movement of the platen 7 under the impulse of 90 the springs 8 is limited by work clamps 13 in the form of angle bars extended longitudinally of the platen and secured to the side bars 3 of the frame immediately above the transverse frame bars 5 and 6. The 95 horizontal portions of these work clamps 13 extend over and along the side margins of the platen and are grooved, as indicated at 14, for the reception of the well known forms of transverse work guarding members 15 or- 100 dinarily employed in connection with flat platens, but usually guided by grooves or ways formed directly in the side bars 3 of the frame. When unresisted the springs 8 urge the platen upwardly and cause a sheet 105 or sheets imposed thereon to be clamped be-

tween the platen and the clamps 13. In the particular use of the platen to which the present invention is more particularly directed, though by no means limited thereto, the work sheet is in the form of a folded form the lower layer or sheet of which is somewhat wider than the upper layer, and has its margin extended between the platen and the left hand work clamp 13, while a 10 ribbon 16 extended longitudinally over the platen is interposed between the upper and lower sheets of the form to transfer matter printed upon the upper sheet to the lower sheet of said form.

15 In order that the platen may be freely movable vertically while guided accurately in such movement, I prefer to provide said platen at opposite sides thereof with guide rollers 17 engaging the side bars 3 of the 20 platen frame and carried by roller brackets 18 screwed or otherwise secured to the under side of the platen, see Figs. 1 and 6. The platen is designed to be depressed by foot power exerted upon a treadle 19 fulcrumed, as indicated at 20, upon a fixed part, as for instance one of the bars 21 of a table upon which these platen frames are ordinarily carried. The treadle 19 is connected by a flexible piece 22 with a platen 25 depressing lever 23 fulcrumed on a fulcrum bracket 24 secured to a fixed part, as for instance the transverse bar 6 of the platen frame. Intermediate of its ends the lever 23 is afforded a pivotal connection, as indicated at 25, with the platen 7. The manner of securing the flexible piece 22 to the lever 23 is not material, but a simple arrangement consists in providing the outer end of the lever 23 with a headed stud 26 30 over which the flexible piece or cable 22 is passed and thence extended to and securely held by a clamp 27 carried by the lever. It will be seen that the platen is normally held in the writing plane by the springs 8, but 35 40 45 50 55 60 65 70 75 80 85 90 95 100 105 110 115 120 125 130

It has been stated that the opposite ends 50 of the ribbon 16 are wound upon rolls. By reference more particularly to Fig. 4, it will be seen that these rolls are carried by front and rear ribbon spools 28 and 29, the spindles 30 and 31 of which are afforded bearings in the side bars 2 and 3 and extended beyond the bar 3 to accommodate knurled heads 32 by means of which the ribbon spools may be rotated by hand if desired. It is intended, however, that line spacing 60 of the ribbon shall be effected automatically, at least each time the platen is depressed for the adjustment or replacement of a work sheet. To this end the spindle of the rear ribbon spool is equipped with a ratchet wheel 33 65 with which coacts a spacing pawl 34 carried

by a spacing lever 35 fulcrumed at 36 on the frame bar 3 and having an upturned end 37 extending forwardly to a position beneath the platen 7. The pawl 34 is urged toward the ratchet as usual by a spring 38 and the lever 35 is normally retained in the position indicated in Fig. 2 by a spring 39 secured at one end to the lever and at its opposite end to the platen frame. By reason of this arrangement, it will be seen that upon the depression of the platen the latter will swing the forward end of the lever 35 thus elevating the rear end thereof and causing the dog 34 by engagement with the ratchet 70 75 80 85 90 95 100 105 110 115 120 125 130

It will of course be understood that in the type of machine to which this invention relates the machine proper, not illustrated, is designed to travel longitudinally of the platen on stationary tracks or guides, and supports downwardly acting printing mechanism by means of which the record may be typewritten on a work sheet sustained by the flat platen. In the present instance the upper edges of the side bars 2 and 3 of the platen frame constitute the tracks or guides for the traveling machine and are therefore toothed, as indicated at 42, for coaction with the line space pinions ordinarily employed on machines of the class mentioned.

It is thought that from the foregoing, the construction, operation and advantages of the invention will be clearly understood, but, while the illustrated structure is thought at this time to be preferable, I reserve the right to effect such changes, modifications and variations thereof as may come fairly within the scope of the protection prayed.

What I claim is:—

1. The combination with a vertically movable platen, of a pair of spools for a flexible strip, and feeding mechanism coöperating with one of the spools and operated by the platen.

2. The combination with a depressible platen, of means for supporting and guiding a flexible strip extended over the platen, feeding mechanism coöperating with the

strip and platen to feed the strip when the platen is moved.

3. The combination with a vertically movable platen, of a pair of ribbon spools, and a pawl and ratchet mechanism operated by the platen to rotate a spool.

4. The combination with a platen frame, of a vertically movable platen mounted therein, a pair of ribbon spools, pawl and ratchet mechanism for rotating one of the spools, and a lever fulcrumed on the platen supporting frame to operate the pawl and ratchet mechanism and having one end extended under the platen to be engaged and operated by said platen when the latter is depressed.

5. The combination with work-holding means, of a flat platen coöperating therewith and vertically movable relative thereto, means for supporting a ribbon in coöperative relation with the platen, and ribbon feeding means coöperatively related to the platen.

6. The combination with a work-holder and a vertically movable flat platen coöperating therewith, of means for supporting a ribbon in coöperative relation with the platen, ribbon feeding mechanism operated by the movement of the platen, and means for moving the platen.

7. The combination with a work-holder, of a platen yieldingly supported in coöperative relation with said work-holder, ribbon supporting means and ribbon feeding mechanism coöperatively connected with the platen.

8. The combination with a work-holder, of a flat platen coöperatively related thereto,

reactive supporting means for the platen, ribbon feeding mechanism, and means for establishing a coöperative relation between the platen and the ribbon feeding mechanism.

9. The combination with a work-holder, of a platen, means for moving the platen, ribbon mechanism operated by movement of the platen, and spring supporting means for returning the platen to its normal position.

10. The combination with a flat platen, of ribbon feeding mechanism, means for depressing the platen to operate the ribbon feeding mechanism, and reactive supporting means yieldingly retaining the platen in normal position and adapted to restore the platen to such normal position after the platen has been operated to feed the ribbon.

11. The combination with a flat platen, of springs supporting the platen and permitting movement thereof toward and away from the normal position of the platen and ribbon feeding mechanism operated by the movement of the platen.

12. The combination with a platen and a work-holder coöperatively related for relative movement to engage and release an interposed sheet, of a ribbon mechanism and means for effecting the automatic feed of the ribbon upon the relative movement of the platen and work-holder.

In testimony whereof I affix my signature in presence of two witnesses.

HARRY A. FOOTHORAP.
